APPARATUS FOR PRODUCING FIXED
COMBUSTIBLE GASWilliam B. Wingert, New York, N. Y., assignor to
Semit-Solvay Engineering Corporation, New
York, N. Y., a corporation of New York

Application July 30, 1931, Serial No. 553,942

4 Claims. (Cl. 261—92)

This invention pertains to apparatus for the production of finely divided dispersed particles of liquid in suspension in a gaseous media and more particularly for the production of a substantially fixed combustible gas containing finely divided liquid particles of the character of fog in suspension therein. The gas containing the fog particles is fixed in the sense that it is relatively stable, i. e. while some of the fog particles 10 separate out on the walls of the long distribution mains in the passage of the gas containing the fog particles therethrough a considerable portion of the fog particles initially introduced into the gas stream is carried in suspension therein throughout the flow of the gas through the mains. The term "fog" is intended to include finely divided liquid particles of the fineness of condensed water-vapor suspended in the atmosphere at or near the earth's surface as frequently encountered particularly in the neighborhood of large bodies of water and as distinguished from water-vapor as such and larger particles of liquid which do not remain in suspension in a gaseous medium for a considerable period of time. 20 One object of this invention is to provide an apparatus for introducing oil, tetralin, water, odorizing liquid such as ethyl mercaptan, etc., into a stream of combustible gas such as water gas, both carburetted and uncarburetted, coke oven gas or natural gas. Other objects of this invention will be apparent from the following description thereof.

The preferred embodiment of this invention involves a container having a gas inlet in one end wall and a gas outlet in the opposite end wall. A partition is disposed at the base of the container from side to side thereof. This partition extends only a relatively short distance from the base so as to provide a substantially unobstructed space 40 at the top of the container. The container is divided into two compartments by this partition, one associated with the gas inlet and the other with the gas outlet. A float valve-controlled conduit is disposed in the compartment 45 associated with the gas inlet to maintain a substantially constant level of liquid in this compartment. This float-controlled valve functions to feed additional liquid into the compartment when the level therein drops below a predetermined point and to reduce the flow when the level rises above this point.

The other compartment has positioned therein a weir disposed parallel to and spaced from the partition defining an end wall of the compartment. An adjustable needle-valve is provided

in the partition to regulate the flow of liquid from the compartment into which the liquid is initially introduced to the weir. The needle valve permits only a regulated steady flow of liquid to the weir and thereover into the other compartment where a substantially constant level of liquid is maintained. A rapidly rotating roll is journaled in the second compartment with its axis substantially parallel to the body of liquid therebeneath and its surface in tangential contact with this 10 body of liquid. The body of liquid is maintained at a substantially constant level beneath the rotating roll by regulating the flow through the needle valve to correspond with the amount of liquid fog taken up by the gas. Due to the needle 15 valve which permits a steady uniform flow to the weir, surges of liquid over the weir with consequent fluctuations in the liquid level beneath the roll are avoided.

A baffle plate is disposed near the top of the compartment into which liquid is initially introduced and is arranged to discharge large liquid particles formed by the rotating roll into this compartment. Hence, if for any reason the level of the body of liquid should rise so that the surface 20 of the rotating roll is partially immersed, large liquid particles formed by the rotating roll would be deflected into the other compartment and thus the level of liquid beneath the roll would be restored to the proper minimum point.

Baffle plates are associated with the gas outlet to remove any liquid particles of a size greater than fog particles. These baffle plates conserve the liquid and since they remove the large liquid particles they prevent subsequent condensation 35 thereof in the gas mains. The gas leaving the apparatus is a substantially fixed gas since it contains fog particles in suspension therein, the particles of a size larger than fog having been removed therefrom.

In the drawing which shows for the purpose of exemplification the preferred form of fogging apparatus to which the invention herein is not confined,

Fig. 1 is a fragmentary plan view of an installation embodying this invention;

Fig. 2 is a vertical section partly in elevation of the fogging apparatus taken in a plane passing through line 2—2 of Fig. 3;

Fig. 3 is an end elevation of the apparatus of Fig. 2, and

Fig. 4 is a fragmentary vertical section through a compartment of the fogging apparatus showing the float controlled valve supplying liquid to this compartment.

In the drawing with particular reference to Fig. 2, the fogging apparatus comprises a container 11 defined by end walls 12, 13, side walls 14, and base 15. A cover member 16 adapted to 5 be readily removed from the container allows access to the interior thereof. A gas inlet 17 is provided in end wall 12 for gas entering the container and a gas outlet 18 is formed in wall 13 for the exit of gas containing fog in suspension 10 therein from the container. A clean-out plug 20 is provided at the base of end wall 12.

A partition 21 extends from side to side of container 11 and is welded or otherwise secured to base 15 and sides 14 to form compartments 22 and 15 23. Partition 21 preferably shaped as shown in Fig. 2 extends only a relatively short distance above the base leaving the top portion of the container unobstructed. Compartment 22 receives liquid initially fed to the container. For this 20 purpose valve-controlled pipe 24 leads from tank 25 or other source of supply of liquid into compartment 22. Pipe 24 is provided with a valve port 26 the flow through which is governed by valve stem 27 operatively connected to a float 25 lever 28 carrying at one end float 31 and having the other end suitably pivoted in compartment 22. Float 31, valve 26 and valve stem 27 are adjusted to maintain a level of liquid in compartment 22 within relatively narrow limits. If the 30 level drops float 31 descends to increase the extent of opening of valve 26 and consequently increase the amount of liquid fed into the compartment to restore the level of liquid to the desired normal point. Conversely, if the level of liquid 35 in compartment 22 rises valve 26 is closed to reduce the flow of liquid thereinto and restore the level of liquid therein.

A weir 32 is welded or otherwise secured to base 15 in the compartment 23. The top of weir 32 40 may be serrated to cause even flow of liquid thereover. The flow of liquid to the weir is controlled by needle valve stem 33 disposed within a valve port or orifice 34 in partition 21. Needle valve stem 33 extends through suitable packing gland 45 35 in end wall 12 and is provided with a hand wheel 36. By turning hand wheel 36 the conical end of valve stem 33 is adjusted with respect to the orifice 34 in partition 21.

The construction of needle valve and weir 50 hereinabove described causes a smooth even flow of liquid in compartment 22 to the weir 32 and thereover onto a body of liquid 37 maintained under rapidly rotating roll 38 hereinafter more fully described. Surges of liquid flowing through 55 main 24 into compartment 22 are confined to compartment 22 and are not communicated to the weir 32 since the needle valve 33 permits only a smooth uniform flow of liquid to take place there-through. Hence the level of the body of liquid 60 37 is maintained at a substantially constant level beneath the rapidly rotating roll 38.

Roll 38 is rotatably journaled in compartment 65 23 with its axis parallel to and its surface substantially tangential to the body of liquid just touching the liquid as shown in Fig. 2. The roll may be in the form of a smooth or perforated cylinder, a wire screen or a plurality of spaced discs and is rapidly rotated by electric motor 39 indicated diagrammatically in Fig. 1. Needle valve 33 is ad- 70 justed so that the liquid fed to weir 32 and thereover corresponds to the amount fogged and consequently the level of liquid beneath the roll remains constant.

A baffle plate 41 extending from side to side in 75 container 11 is welded or otherwise secured to the

sides. This baffle plate is disposed to partially cover gas inlet 17 and is arranged as indicated in Fig. 2. It thus prevents the entrance of liquid particles into the gas conduit leading into container 11. If for any reason the level of the body 8 of liquid 37 rises so that roll 38 becomes partially immersed, the liquid particles of substantial size which will then be formed will be thrown onto baffle 41 which in turn discharges the liquid particles into compartment 22. Thus the level of liquid beneath the roll 38 is restored such that the roll surface just contacts therewith and a fog of liquid above the roll is produced.

Baffle plates 42 arranged in staggered formation are suitably mounted in front of the gas outlet 15 18, so that the mixture of gas and fog particles leaving the container contact and pass over the baffles. These baffles remove any liquid particles of a size greater than fog carried by the gas leaving the fog particles in suspension therein. 20 Hence the gas removed from the container 11 contains only fog particles in suspension and is a substantially fixed gas.

In Fig. 1 there is shown the application of the gas fogging apparatus to distributor main 43. 25 Main 43 is provided with an orifice plate 44 and by-pass mains 45 and 46 disposed on opposite sides of the orifice plate. By-pass 45 and 46 are connected to the gas inlet 17 and gas outlet 18 respectively. The amount of gas conducted 30 through the by-pass pipes into and through the fogging apparatus is controlled by suitable hand valves 47 and 48 in pipes 45 and 46 respectively. A definite proportion of the gas flowing through main 43 passes through the orifice plate 44, the 35 remainder of the gas passing through by-pass 45 into and through container or box 11 wherein it contacts with the fog created by the rapidly rotating roll 38, the resultant fixed gas containing the fog in suspension passing through by- 40 pass 46 into the main distributor pipe 43 where it becomes intimately admixed with the gas flowing through the orifice plate 44 and main 43. Due to the relative positions of orifice plate 44 and by-pass 46, a zone of reduced pressure is 45 formed by the stream of gas issuing at high velocity adjacent the point where by-pass pipe 46 joins main 43. The reduced pressure assists in drawing the gas having the fog in suspension 50 therein from the fogging apparatus into the main conduit 43 and the turbulence associated with the jet of gas issuing from the orifice causes thorough and intimate mixture of the gas containing the fog in suspension with the gas flowing through orifice plate 44 and main 43 to the 55 left of the orifice viewing Fig. 1.

It will be noted that in accordance with this invention combustible gas may be effectively and thoroughly fogged with oil, tetralin or other liquid, the fog formed by the rotating roll extending 60 across the full cross-section of the container 11 through which the stream of gas passes and resulting in the production of a substantially fixed gas containing the fog in suspension.

The invention is herein disclosed as embodied 65 in a particular form of construction but it is to be understood that it may be variously embodied within the scope of the appended claims.

I claim:

1. Apparatus for producing a substantially 70 fixed gas containing fog particles in suspension comprising a container having a gas inlet and a gas outlet, a partition dividing said container into two compartments, means for introducing liquid to be fogged into one of said compart- 75

- 5   ments, a weir disposed in the other of said compartments spaced from said partition, a needle valve controlling a port in said partition for regulating the flow of liquid from said compartment into which the liquid is introduced to said weir, said weir being arranged to provide substantially constant flow of liquid in the other of said compartments on the side of the weir remote from said partition, and a roll rotatably mounted in 10 said other compartment with its axis substantially parallel to the upper surface of the body of liquid and its surface substantially tangential to said body of liquid.
- 10   2. Apparatus for producing a liquid fog comprising a container, a partition dividing said container into two compartments, means for introducing liquid to be fogged into one of said compartments, a weir disposed in said other compartment spaced from said partition, means for providing a controlled flow of liquid from said compartment into which liquid to be fogged is introduced to said weir, said weir maintaining a substantially constant level of liquid in the compartment in which it is positioned, a roll rotatably mounted in said other compartment with its axis substantially parallel to the upper surface of the body of liquid and its surface substantially tangential to said body of liquid, and means for rotating said roll to create liquid fog particles.
- 15   25   3. Apparatus for producing a gas containing fog particles in suspension therein, comprising a container having a gas inlet in the neighborhood of the top of one end wall and a gas outlet in the neighborhood of the top of the opposite end wall, a partition extending across the base of said container from side to side thereof dividing it into two compartments one having a gas inlet leading thereto and the other having a gas outlet leading therefrom, the partition extending only part way up from the base of said container so that the upper portion thereof is unobstructed, a float-controlled valve for maintaining a 30 substantially constant level of liquid in said compartment having the gas inlet leading thereto, a weir in the other of said compartments spaced from said partition, a needle-valve controlling an orifice in said partition, said needle-valve governing the flow of liquid through said partition to said weir, said weir maintaining a substantially constant level of liquid in said other compartment, a roll rotatably mounted in said other compartment with its axis substantially parallel to the upper surface of the body of liquid and its surface substantially tangential to said body of liquid, and means for rotating said roll to create liquid fog particles.
- 20   35   4. Apparatus for producing a substantially fixed gas containing fog particles in suspension therein comprising a container having a gas inlet and a gas outlet, a partition dividing said container into two compartments, means for introducing liquid to be fogged into one of said compartments, a weir disposed in the other of said compartments spaced from said partition, a needle valve controlling an orifice in said partition regulating the flow of liquid from said compartment into which liquid is introduced to said 25 weir, said weir being arranged to provide a substantially constant level of liquid in the other of said compartments on the side of said weir remote from said partition, a roll rotatably mounted in said other compartment with its axis 30 substantially parallel to the upper surface of the body of liquid and its surface substantially tangential to said body of liquid, means for rotating said roll to create liquid fog particles, a baffle plate below said gas inlet arranged to discharge liquid particles formed by said roll into said compartment into which liquid to be fogged is introduced, and a baffle disposed over said gas outlet to remove liquid particles from the gas-fog mixture of a size greater than the fog particles.
- 25   40   WILLIAM B. WINGERT.
